CONTAINER AND CLOSURE WITH OPENING
MEANS THEREFOR

Pasquale V. Di Cosmo, Phillipsburg, N. J., assignor to The Canister Company, Phillipsburg, N. J., a corporation of New Jersey

Application December 3, 1942, Serial No. 467,804

5 Claims.

(Cl. 229—51)

This invention relates to containers and the like and particularly to constructions whereby containers may be effectively sealed but are capable of being readily opened and emptied.

Containers embodying the present invention may be formed of any preferred material and may be used for storing and shipping products in any desired form, such as liquids, pastes or powders. However, for purposes of illustration the containers hereafter described in detail are formed of fibrous material and are designed for use with liquids, such as lubricating oil.

Containers used heretofore for lubricating oil have generally been tin cans and have been opened by puncturing the top of the can and turning a portion of the metal inward adjacent the edge of the can. This method of opening containers is objectionable because the material turned inward obstructs the flow of liquid from the container so that complete emptying thereof is difficult whereas the stream of liquid formed is frequently divided or irregular and cannot be easily directed. Moreover, metal containers are expensive and are not available for many purposes at the present time. On the other hand containers formed of fibrous materials, when thick or heavy enough for the storage and shipment of oil are difficult to seal and when punctured or opened by tearing they present rough fibrous edges from which loose fibers and fragments are removed by the oil and carried into the crank case of the engine where they clog pipe lines, pumps, filters and other mechanism.

In accordance with the present invention a fibrous container is provided which possesses the requisite strength for use as a container for oils, paints and other materials but the sealing of the container is established by the use of thin flexible means and an oil resistant sealing compound. Moreover, the container is formed with a portion capable of being displaced to provide a free unobstructed discharge opening adjacent the edge of the container while the surfaces contacted by the oil on discharge thereof are clean, smooth and free of all loose fibers or portions which might contaminate the oil.

In general, containers embodying the present invention have a closure member which includes a relatively stiff, strong closure element formed of chip-board, kraft or other paper stock, and a thin flexible sealing element made of oil and liquid resistant parchment paper, Cellophane, metal foil or other material which may be torn but does not present any free, loose fibers capable of ready removal. The stiff portion of the

closure member is pre-cut by a sharp die or other tool along spaced lines which extend inward from the edge of the disc so as to provide a displaceable portion with a smooth clean surface for contact with the material being discharged from the container. Containers so formed are strong, and leak-proof as well as being neat and attractive in appearance. Moreover, they are also tamper-proof in that they cannot be opened without being rendered unsuitable for reuse.

One of the objects of the invention is to provide novel and economical methods and means for sealing a container while providing for ready opening thereof.

15 Another object of the present invention is to provide a novel type of container formed of fibrous material and having displaceable means movable to form a discharge opening having smooth, clean edges free of loose fibers or broken fragments which might contaminate the contents on discharge thereof from the container.

20 A further object of the invention is to provide a container with displaceable means to form a discharge opening in the container and means 25 for sealing the container serving to hold the displaceable means in place.

A further object of the invention is to provide an improved tamper-proof and nonrefillable fibrous container.

30 These and other objects and features of the invention will appear from the following description thereof in which reference is made to the figures of the accompanying drawing.

In the drawing:

35 Fig. 1 is a perspective of a portion of a container and closure member embodying the present invention and arranged in position for assembly.

Fig. 2 is a view similar to Fig. 1 showing the closure member in position on the container.

40 Fig. 3 is a vertical sectional view of the construction shown in Fig. 2 with the closure member fixed in place, and

Fig. 4 is a vertical sectional view through the sealed container with the displaceable portion moved to open the container.

In that form of the invention illustrated in the drawing the body of the container is shown at 2 and preferably is formed of spirally wound fibrous material such as chip-board, kraft paper or other fibrous stock having a liner 4 of oil resistant material such as parchment paper on the inner face thereof. Container bodies of this general type are described in the patent to Kernahan No. 2,202,558. The end closure member 6 of the container embodies a disc 8 formed of stiff material

such as chip-board and a liner or sealing element 10 located adjacent the lower or inner face thereof.

The disc 8 includes the displaceable portions 12 which are formed by cuts 14 which as shown 5 extend radially inward from the edge 16 of the disc to points 18 spaced from the center of the disc. It is preferable to form a score line 20 on the upper surface of the disc and extending from the inner extremity 18 of one cut 14 to the inner 10 extremity of the other so that the displaceable portion 12, the cuts 14 and the score line 20. If desired a second score line 22 may be formed in the lower face of the disc to increase the flexibility of the disc at the score line without materially weakening the disc.

The cuts 14 are formed in the disc by means of a die or a sharp instrument which serves to form a clean, smooth cut edge 24 having no free fibers or broken parts which might become disengaged or removed by the oil or other material as it flows in contact therewith. The score line 20 does not extend through the disc but serves only to define a hinge or line of bending so that the portion 12 may be forced inward to the position shown in Fig. 4 to open the container without breaking the disc along the score line or causing it to rupture or expose any rough fibrous surface.

The disc 8 is preferably secured to the sealing element 10 so that both may be applied to the container body as a unit and in a single operation. For this purpose the disc 8 is cut from a flat sheet of chipboard and the cuts 14 are formed therein by means of a die or other tool while the sealing element 10 is similarly cut from a flat sheet of parchment paper and has a larger diameter than the disc 8. These parts are then assembled and secured together by means such as the glue 26. The glue preferably does not extend to the cuts 14 and therefore it does not prevent ready displacement of the portion 12 or cause the material at the edges of the cuts to be broken away when the container is opened.

The disc 8 and sealing element when so assembled form the closure member 6 which is shown in Fig. 1 in position to be applied to the container body 2. In applying the closure member a sealing composition such as glue 28 is applied to the rim 30 of the body and extends over the inner and outer surfaces 32 and 34 respectively of the body adjacent the rim. The disc and sealing element are then moved axially toward the container body to a point slightly inward from the rim 30 as shown in Fig. 2. At the same time the portion 36 of the sealing element near the edge 16 of the disc 8 is turned upward and formed to the shape of the glue bearing inner surface 32 of the container body while the outer marginal portions 38 of the sealing element are turned downward about the outer glue bearing surface 34 of the container body. As the disc 8 is forced into the end of the container the portions 36 and 38 of the sealing element are caused to wipe over the glue 28 so that the glue is spread over the sealing element and is folded into wrinkles or crevices in the formed portions 36 and 38 to completely seal the joint between the sealing element and the container body. Moreover, since the diameter of the stiff disc 8 is substantially equal to the internal diameter of the body, the sealing element is squeezed or forced against the inner surface 32 during this operation. As a result of this squeezing any ex-

cess glue beyond that required for effectively sealing the space between the sealing element and the liner 4 of the body is forced inward so as to form a continuous gasket of sealing compound 40 at the joint between the sealing element and the liner 4. This gasket provides a smooth, continuous air-tight and liquid-tight joint which seals any pinholes, wrinkles or crevices which might remain unsealed by the forming of the sealing element to the adjacent surface of the container body. The spreading and flow of the sealing compound or glue is aided if the operation is performed by means of a heated die.

While forcing the disc 8 into the end of the container body the sealing element 10 is stretched taut against the lower face of the disc and serves to support the disc rigidly in place. The displaceable portion 12 of the disc is thereby supported from below by the sealing element and the free edge 16 of portion 12 is further supported by the gasket of glue or sealing compound 40 beneath the sealing element. In completing the sealing of the container the rim 28 is turned inward over the outer marginal portion of the disc 8 to form the retaining bead 44 so that outward movement of the disc or displaceable portion 12 is prevented.

In this way the disc 8 is firmly clamped between the sealing element and bead 44 so that the closure member is rendered strong enough to withstand any ordinary impacts or forces to which the container may be subjected during shipping, handling or storage thereof.

All of the operations required for applying the closure member may be performed simultaneously by means of a die which pushes the disc 8 into the end of the body at the same time that it turns the marginal edges of the sealing element downward about the outer surfaces 34 of the body. During the final stage of movement of the die toward the container body the portion thereof which turns the sealing element down about the rim 30 forces the rim inward to form the retaining bead 44. By using a heated die the fluxing of the sealing compound and the molding of the rim into the bead 44 are facilitated.

After the container has been sealed as described a label or wrapper 46 is applied about the body of the container with the edges of the label extending over the edges 38 of the sealing element so that a neat attractive finished container is obtained. However, when, as is preferred, the container is filled from the opposite end and thereafter sealed by the method and construction described in the application for patent of Di Cosmo Serial No. 467,805 filed December 3, 1942, the wrapper 46 is not applied until after such operations have been performed.

When it is desired to open the container a blunt instrument is pressed against the displaceable portion 12 of the disc to push it inward. When pressed hard enough the sealing element 8 is ruptured, the supporting sealing gasket of glue 40 is broken and the portion 12 is turned inward about the score lines 20 and 22 to the position shown in Fig. 4 forming a discharge opening 48. Moreover, it is found in practice that, the portion of the liner 4 of the container body adjacent the portion 12 of the closure disc 8 is so bonded to the adjacent portion of the diaphragm that when the portion 12 of the disc is forced inward and the diaphragm ruptured in opening the container, a portion of the liner 4 is torn downward and stripped from the fibrous body of the container. In this way, the body is

exposed to the contents of the container as they are poured therefrom and the container body is softened and permeated by liquid so that it becomes weakened and contaminated, and the container may not again be reused. The sealing element, being formed of parchment paper or other material which does not yield free fibers or loose bits of material, does not contaminate the oil whereas the smooth cut surfaces 24 on the inner edge of the opening 48 and on the outer edge of the displaceable member are also free of any loose detachable fibers. The oil can then be discharged through the discharge opening without danger of contamination and without obstruction so that the container may be completely emptied. Furthermore sealing element 10 is destroyed in opening the container and displacement of the portion 12 produces such distortion of the fibrous disc that it cannot be restored to permit reuse of the container or substitution of its contents. The container is therefore tamper-proof.

I claim:

1. A container having a body of circular cross section provided with means closing the end thereof comprising, a rupturable sealing element extending across the end of the body and secured thereto, and a disc formed of stiff material positioned wholly within the body and having spaced cuts extending inward from the periphery thereof to provide a displaceable portion having a free edge located adjacent the inner surface of the container body, said disc overlying the sealing element and being held in place with its edges adjacent the container body so that the free edge of the displaceable portion of the disc between said cuts is capable of being moved inward to rupture the sealing element and form a discharge opening in the disc.

2. A container for liquids having a body of circular cross section formed of fibrous material and lined with sheet material with means closing the end of the body comprising, a liquid resistant parchment sheet which extends across the end of the body and has its marginal portions secured to the liner of the body while the center thereof is located inward from the extremity of the container body, a closure element formed of a disc of stiff fibrous material positioned wholly within the body and having spaced sharply defined cuts extending inward from the periphery thereof to provide a displaceable portion having a free edge adjacent the liner of the container body, said disc engaging and being supported by the central portion of the sealing element, the extremity of the container body being turned inward over the edge of the disc to hold it in place whereby the free edge of the displaceable portion of the disc between said cuts may be forced inward to rupture the sealing element and form an unobstructed discharge opening from which the contents of the container may be poured.

3. A container having a body of circular cross section with means closing the end thereof comprising, a rupturable sealing element extending across the end of the body and secured thereto, and a disc of stiff fibrous material positioned wholly within the body and with spaced sharply defined cuts extending inward from the periphery of the disc to provide a displaceable portion having a free edge located adjacent the inner surface of the container body and having their inner extremities joined by a score line, said disc being positioned to engage the sealing element and supported at its edges adjacent the container body whereby the free edge of the displaceable portion of the disc between the cuts may be forced inward about said core line as a pivot to rupture the sealing element and form an unobstructed discharge opening in the end of the container.
4. A container having a body of circular cross section with means closing the end thereof comprising, a rupturable sealing element extending across the end of the body and secured thereto, and a disc of stiff fibrous material positioned wholly within the body and with spaced sharply defined cuts extending inward from the periphery of the disc to provide a displaceable portion having a free edge located adjacent the inner surface of the container portion and having their inner extremities joined by a score line, said disc being positioned to engage the sealing element and supported at its edges adjacent the container body, the rim of the container body being turned inward over the edges of the disc to hold it in place, whereby the free edge of the displaceable portion of the disc between the cuts may be forced inward about said score line as a pivot to rupture the sealing element and form an unobstructed discharge opening in the end of the container.
5. A container having a body formed of fibrous material and lined with sheet material with means closing the end of the body comprising, a sheet which extends across the end of the body and has its marginal portions secured to the liner of the body while the center thereof is located inward from the extremity of the container body, a closure element formed of a disc of material positioned wholly within the body and having cuts extending inward from the edges thereof to provide a displaceable portion having a free edge adjacent the liner of the container body, said disc engaging and being supported by the central portion of the sealing element, the end of the container body being turned inward over the edge of the disc to hold it in place whereby the free edge of the displaceable portion of the disc between said cuts may be forced inward to rupture the sealing element and form an unobstructed discharge opening from which the contents of the container may be poured.

PASQUALE V. DI COSMO.
